UNITED STATES PATENT OFFICE

154,007

DESIGN FOR A WOMAN'S OVERSHOE

Harold A. Watkins and Elsmer M. Heimerl, Milwaukee, Wis.; said Heimerl assignor to said Watkins

Application April 10, 1948, Serial No. 145,644

Term of patent 14 years

(Cl. D7—4)

To all whom it may concern:

Be it known that we, Harold A. Watkins, a citizen of the United States, residing at Milwaukee, in the county of Milwaukee and State of Wisconsin, and Elsmer M. Heimerl, a citizen of the United States, residing at Milwaukee, in the county of Milwaukee and State of Wisconsin, have invented a new, original, and ornamental Design for Woman's Overshoe, of which the following is a specification, reference being had to the accompanying drawing, forming part thereof.

In the drawing:

Fig. 1 is a side elevational view, slightly in perspective, of a woman's overshoe, showing our new design, the opposite side presenting substantially the same appearance as the side shown;

Fig. 2 is a front view thereof, slightly in perspective.

The claim for novelty is predicated on the loose fitting appearance of the overshoe including the raised portion above the instep, and the high sub-

stantially vertical toe front, in combination with the far downwardly extending zipper opening arrangement, all as illustrated.

We claim:

The ornamental design for a woman's overshoe, substantially as shown and described.

HAROLD A. WATKINS.
ELSMER M. HEIMERL.
